UNITED STATES PATENT OFFICE.

WARREN KINZY, OF PIKE, ARKANSAS.

SHOW-CASE.

SPECIFICATION forming part of Letters Patent No. 709,331, dated September 16, 1902.

Application filed May 21, 1902. Serial No. 108,389. (No model.)

To all whom it may concern:

Be it known that I, WARREN KINZY, a citizen of the United States, residing at Pike, in the county of Pike and State of Arkansas, 5 have invented new and useful Improvements in Show-Cases, of which the following is a specification.

My invention has relation to improvements in show-cases; and the object is to associate 10 and combine with the sliding closures of a show-case an alarm device for announcing the movement of the sliding closures and means for holding the slides in extended position when they are drawn to close the case.

15 With these objects in view the invention embodies the novel construction of parts and their assemblage in operative combinations, as will be hereinafter fully specified and the novelty claimed particularly and distinctly 20 pointed out.

I have fully and clearly illustrated my invention in the accompanying drawings, wherein—

Figure 1 is a plan view, partly in horizontal 25 section. Fig. 2 is a view in vertical elevation of the alarm mechanism and longitudinal vertical section through the casing thereof and through the show-case. Fig. 3 is a detail view, partly in transverse section, through 30 one of the alarm mechanisms.

Similar reference-notations refer to similar parts throughout the several illustrations.

Referring to the drawings, it will be perceived that the general construction includes 35 a casing arranged at the middle of the show-case, wherein are mounted duplicate winding mechanisms contacting with hammer-rods, an interposed bell to receive the strokes of the hammers, and connections to the sliding 40 closures of the show-case.

More particularly describing the mechanism by which I attain the objects of my invention, A designates a show-case of any suitable construction provided with sliding closing plates 1 2, running parallel with each other in grooves 3 4 made in the floor or bottom of the case, and their outer ends engaging in vertical grooves 5 in the inner side faces of the end posts of the show-case, as 45 shown in the drawings in Fig. 1. Of course the upper edges of the slides engage grooves or guide-strips of the case in the usual man-

ner. At the outer end of each slide is secured a plate 6, formed with a catch-lug, with which a latch 7 engages to hold the slides closed. 55

B designates a suitable rectangular casing having end extensions 8, whereby it is secured in position within the casing to the floor thereof, as indicated in the drawings. The casing B is made of such dimensions and 60 capacity as will fit it for the purpose of containing the mechanism mounted and secured therein. The casing is provided with cord-apertures 9, through which the pull-cords pass. In the casing B, at each end thereof, 65 are mounted the bell-ringing mechanism, duplicates in parts and construction, and operating the same, except that their pulling force is in opposite directions. Therefore the description of one applies to both. 70 Referring more particularly to Fig. 3, this mechanism comprises a vertical shaft 10, journaled across the casing and having an angular part 11 and a round part 12. On the part 11 is mounted to turn with the shaft a suitable grooved pulley or spool 13, and contiguous to the lower end of the pulley is loosely mounted a ratchet-wheel 14, secured to or made part of a disk 15, which turns with the ratchet loose on the shaft. On the shaft 10, 75 closely adjacent to the disk, is fixed a small ratchet-wheel 16, engaged by a pawl 17, pivotally mounted on the face of the disk. On the pulley or spool 13 is attached one end of a cord 18, the other end being anchored to a 80 suitable point near the outer end of the slide in the casing.

19 designates a coil-spring having one end anchored to a stationary point in the casing and the other end fastened to the shaft and 85 so arranged that when the cord is extended the spring will be wound up, and when the slide is moved to open the case the spring will turn the spool, take up the cord or wire, and turn the ratchet 14 with the shaft. 90

Midway between the winding mechanism is mounted a bell 20, and pivotally mounted in the casing are two hammers or clappers 21, one end of which impacts with the bell and the other ends engage the ratchet 14. 95

100 It will now be perceived that when the slides are closed and either one be released, the spring will take up the cord on the spool, and also turn the ratchet 14 with the shaft,

and because of the engagement of the end of the clapper therewith that will be oscillated to strike the bell and sound the alarm.

It will be observed that a single device may 5 be used for a case having a single slide.

Having described my invention, what I claim is—

1. The combination with the closing slide of a show-case, of a casing secured in the show-case, a shaft journaled in the casing, a spool fixed on the shaft, a ratchet mounted loose on the shaft, a second ratchet fixed on the shaft, a pawl on the loose ratchet to engage the fast ratchet and lock the first-named ratchet to the shaft in one direction, a coil-spring to rotate the shaft, an extensible and retractable cord having one end secured to the spool and the other end secured to the slide, a bell, and a clapper actuated by the loose ratchet when fast on the shaft. 15 20

2. The combination with the parallel closing slides of a show-case, of a casing mounted in the casing, duplicate shafts journaled in the casing, a spool fixedly secured on each shaft, cords extending from the spools to the outer ends of the slides, combined disks and ratchets loosely mounted on the shafts, a ratchet fixed on the shafts, pawls on the disks to engage the fixed ratchets, springs to actuate the shafts, a bell interposed between the shafts and the mechanisms, and clappers actuated by the loose ratchets, substantially as described. 25 30

In testimony whereof I affix my signature in presence of two witnesses.

WARREN KINZY.
